 2 Claims. (Cl. 101—219)

The present invention relates to a device for performing marking operations, as for instance stamping or printing, on a continuously or intermittently fed material web running over a circular-cylindric roll or drum, whereby the distance between any two operations following in succession in principle may be optionally pre-set.

When performing certain marking operations as for instance stamping, embossing or printing on a material web it is often necessary that the distance between operations following in succession should be adjustable to enable the operations to be effected according to a programme made up beforehand.

When performing marking operations with one known type of apparatus it is known the material web is fed forward between two rolls rotating in concurrence, which are equipped with the tools necessary for performing the marking operation. A device of this type is for instance a rotary printing press, where the paper web is printed when passing through a pair of rolls. A disadvantage with these known devices is, however, that the operations are repeated regularly, wherefore the distances between the processing points on the material web in the main will be equal, provided the tooled roll is not exchanged with a larger or a smaller one.

A device in accordance with the invention is therefore very advantageous when it is required that the marking should be applied on the material web at intervals independent of each other and is characterized therein that a revolving roll provided with the tools necessary for the required marking operation is arranged to engage with the material web under the control of a locking device which is released by means of a programme attachment, in order to perform the mentioned operation when rolling against the material web, and to revolve into a position in which the roll is disengaged from the material web and where it again is locked by the locking device in a disengaged position in relation to the material web.

In the following the invention is described with reference to the enclosed diagrammatical drawing, in which

FIG. 1 illustrates the device with the marking roll in locked position,

FIG. 2 shows the device after the marking roll is released and is rotating clockwise by gravity into engagement with the material web,

FIG. 3 shows the device during performance of the marking operation, and

FIG. 4 shows the position, where the marking roll 4 breaks its contact with the web 1.

In the FIGS. 1 to 4, which accordingly show the same device in different operations, a material web, for instance a paper web, is indicated by reference numeral 1. The web 1 is carried over a roll 2, which revolves around a shaft 3. Another roll 4, which can revolve around shaft 5, is provided with a depressed peripheral portion such as a flat 6 and a weight 10 diametrically opposite the flat 6. The roll 4 is further provided with a locking pin 9 against which a locking bar 8, which is operated by means of a lifting magnet, is arranged to operate. To perform the marking operation a portion of the periphery of the roll 4 is further provided with a stamping tool

11, by means of which stampings 12 in the material web is effected.

In FIG. 1 the device is shown with the marking roll 4 in a locked position. The material web 1 is carried upwards over the roll 2 rotating in concurrence, whilst the roll 4 is not in engagement with the material web 1 and the roll 2 because of the fact that the flat part 6 of the roll 4 faces and is spaced from the material web 1. The roll 4 is retained in the locked position by the locking bar 8 operating against the locking pin 9.

When a marking operation is desired to be effected in the material web 1 the lifting magnet 7 is charged with current from an impulse device, not shown here, which either may be guided by the movement of the material web or its driving machinery or by an entirely optional programme. When the impulse is received electro-magnet 7 lifts the locking bar 8 operating against the locking pin 9 with the effect that the statically unbalanced roll 4 is disengaged and by the eccentrically located weight 10 is turned by gravity clockwise around its shaft 5 into the position shown in FIG. 2. The bottom part of the flat section 6 of the roll 4 is caused by the revolving action of the roll 4 to engage with the material web 1, whereafter this with its upwards action and through friction carries the roll 4 with it to give the roll a practically non-sliding rolling movement along the surface of the material web 1. When the marking roll 4 is rolled along the web 1, as shown in FIG. 3, the stamping tool 11, projecting from the surface of the roll 4, will be forced into the web 1 thereby effecting the stamping operation. After the roll 4 has been turned approximately one revolution it will be in the position, shown in FIG. 4. Here it is again disengaged from the material web 1 when the upper edge of the flat 6 breaks its contact with the web. Owing to the fact that the eccentric weight 10 exerts a turning force on the roll 4 it will continue its clockwise rotation until the locking pin 9 reaches the bar 8 now having again reached its locking position, whereafter the position shown in FIG. 1 is regained.

The material web 1, which through the operations has been provided with stamp indentations 12, continues its upwards movement, whereafter the device is ready to effect a new stamping operation.

As will be seen from the description the operation is not effected at the same time as the impulse is communicated to the lifting magnet 7, and therefore it is necessary to take the distance into account by which the web 1 is fed forward between the moment of impulse and the performance of operation. As this distance, however (disregarding the web movement during the interval between the delivering of the impulse and the moment of contact between the roll and the web) largely is equal on all occasions and practically independent of the speed, in most cases this point does not represent any difficulty.

With the device described herein it is thus possible to carry out marking operations, for instance stamping, in the web-formed material 1 in such a way that the stampings appear at certain intervals or in certain relation to a pattern already printed on the web. In the first mentioned case the marking roll 4 may for instance be released by an impulse attachment which is guided by organs connected with the web drive, and in the latter case by a photo-cell attachment. As previously pointed out it is even possible to guide the impulse attachment, which releases the marking roll, with an optional programme, whereby for instance a punched tape, magnetic tape or something similar may be used to guide the impulse attachment.

With the device described herein it is even possible to vary the sideways position of the marking operation performed by means of moving the rolls 2 and 4 sideways on the shafts 3 and 5, respectively.

As will be seen from the above description, the device permits very wide possibilities of variations with regard to performance of the required operations as well as their position in relation to the material web, wherefore the device has proved to be very advantageous to use especially in cases, where different marking operations are required to be effected with variable distances between them on a material of differing width.

We claim:

1. In a marking mechanism for effecting a marking operation on a surface such as a web moving in a substantially vertical direction, the combination comprising an essentially cylindrical marking member, means mounting said cylindrical marking member for rotation about its axis, a marking element located on a first portion of the periphery of said cylindrical marking member, said cylindrical marking member being eccentrically weighted to one side of said axis of rotation and including a depressed second peripheral portion located to the opposite side of said axis of rotation and so positioned when said cylindrical marking member occupies an initial position, as to establish an initial clearance between the periphery of said cylindrical marking member and said moving surface, locking means for holding said cylindrical marking member in said initial position and against rota-

tion by the force of gravity which would otherwise occur due to its eccentrically weighted characteristic, and means for releasing said locking means thereby to permit an initial gravitational rotation of said cylindrical marking member and which brings said first peripheral portion into frictional driving engagement with said moving surface whereby said marking element is thereafter caused to rotate into position adjacent said moving surface and establish a marking contact with and move in the same direction as said moving surface.

2. A marking mechanism as defined in claim 1 wherein said locking means is constituted by a pin on said cylindrical marking member, a locking bar cooperative with said pin, and means for releasing said bar from said pin.
